UNITED STATES PATENT OFFICE.

WILLIAM H. DILL, OF BUFFALO, INDIANA.

ADJUSTABLE GATE.

SPECIFICATION forming part of Letters Patent No. 366,937, dated July 19, 1887.

Application filed March 9, 1887. Serial No. 230,259. (Model.)

To all whom it may concern:

Be it known that I, WILLIAM H. DILL, a citizen of the United States, and a resident of Buffalo, in the county of White and State of Indiana, have invented certain new and useful Improvements in Adjustable Gates; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 of the drawings is a representation of side elevation of a gate. Fig. 2 is a side elevation with gate raised. Fig. 3 is a detail view of half-hinge rail. Fig. 4 is a detail view.

20 My invention relates to adjustable gates; and it consists in the construction and novel combination of parts, as hereinafter described and claimed.

25 Referring by letter to the accompanying drawings, A designates the hinge-post, and B the latch-post or stop-post.

30 C D designate two vertical parallel rails, which have a block, E, interposed between their upper ends, a block, F, interposed between their lower ends, and a block, G, interposed between them intermediately of said upper and lower blocks, to form the spaces H I between said vertical parallel rails. The lower block, F, and the intermediate block, G, are provided with rearwardly-projecting eyes or half-hinges

35 J K, which engage the upper pintle, L, and the lower pintle, M, when the gate is hung in place. In order to prevent the vertical parallel rails C D from being accidentally lifted from place, a bent rod, N, is secured in the 40 hinge-post A just above the lower pintle, M, and is adapted to be turned up out of the way when it may be desirable or necessary to remove the vertical parallel hinge-rails.

45 P designates the gate-frame, which may be of any ordinary construction, having parallel end battens, Q R, between which one of the rails projects into the space H. Between the upper ends of the battens Q R the front end of a headed arm, T, is pivoted by a bolt, U,

the head of said arm T bearing against the 50 rear edges of the vertical parallel hinge-rails C D, and working in the space I when the gate-frame is adjusted vertically. This headed arm T is the upper guide-piece in adjusting the gate.

55 The projecting end of the rail S is provided with two bolt-holes made laterally through it, one for the reception of the bolt V, which is seated in either one of the aligned bolt-holes W made transversely through the vertical 60 parallel rails C D, and the other for the reception of a guide-pin, X.

By removing the bolt V the gate-frame may be adjusted vertically, should it be in the lower position, to raise it to permit small stock to 65 pass under it when closed, or to swing over snow when the ground is covered with snow, or, should it have been previously elevated, to lower it to exclude small stock.

65 By the employment of the vertical parallel 70 rails C D a swinging gate already constructed may be easily changed to adapt it to operate in connection with the rails C D.

In their inner faces near their lower ends, and at intervals for some distance above their 75 lower ends, the vertical rails C D are provided with several pairs of downwardly and rearwardly inclined spur-seats a, which are designed to receive spurs b b projecting rearwardly from the rear faces of the rear battens, 80 Q R, said spurs and seats being designed to assist in holding the gate to its vertical adjustment.

The object of pivoting the arm T is to permit the disengagement of the spurs b from their 85 seats when adjustment of the gate-frame is to be made.

Having described my invention, what I claim, and desire to secure by Letters Patent, is—

90 1. The combination of the hinge-post provided with pintles and the gate-frame provided with the projecting rail having a transverse bolt-hole, the perforated vertical parallel hinge-rails having the spaces H I and the 95 half-hinges, the headed arm passed through the space H and pivoted between the upper ends of the rear end battens of the gate-frame,

and the adjusting-bolt in the perforated vertical hinge-rails, substantially as specified.

2. The combination, with the perforated vertical parallel hinge-rails provided with the 5 spur-seats in the front faces of the rails, of the gate-frame provided with the projecting spur for said seats on its parallel perforated hinge-rails, substantially as specified.

In testimony whereof I affix my signature in presence of two witnesses.

WILLIAM H. DILL.
